UNITED STATES PATENT OFFICE.

JEROME WARREN CHASE, OF PORTLAND, MAINE.

GAME APPARATUS.

1,168,854.

Specification of Letters Patent. Patented Jan. 18, 1916.

Application filed April 7, 1915. Serial No. 19,651.

To all whom it may concern:

Be it known that I, JEROME WARREN CHASE, of Portland, in the county of Cumberland and State of Maine, have invented 5 certain new and useful Improvements in Game Apparatus, of which the following is a specification.

My invention relates to a game apparatus of that class wherein rings or other annular pieces are projected and caught on projections of various kinds.

The object of the invention is to provide a game apparatus which may be cheaply manufactured and which will furnish the 15 means of playing an interesting game.

The invention consists of the features of construction hereinafter described and claimed.

My invention is illustrated by means of 20 the accompanying drawing in which is shown my improved game apparatus in its approved form.

Referring to the drawing, Figure 1 is a perspective view of the game board with 25 the parts in place ready for the game, Fig. 2 is a like view of the catapult or ring projector in position to toss a ring onto the board, Fig. 3 is a longitudinal section through Fig. 2 and Fig. 4 is a central vertical section through Fig. 1, and Fig. 5 is a modified form of the catapult.

Referring to the drawing, 1 represents a board which contains a series of holes symmetrically arranged. The board is preferably made of thin material like pulp board 35 and the holes are of just sufficient size to allow the passage of playing pins 3. The pins are arranged as here shown in a series of concentric circles with one pin in the center.

The sides of the board have downwardly extending flanges and these fit within the flanges of an open topped box 2. The board 1 and the box 2 when placed together 45 form a stable and rigid foundation for holding the pins in an upright position.

The lower end of the pins are held in place by passing through a diaphragm 4 which may be a sheet of pulp board separated from the bottom of the box 2 by transverse strips 5. When the pins are not in use or playing the game they, with the other parts of the apparatus are inclosed in the box which thus forms a container as 55 well as a game board.

The pins are numbered and are given certain arbitrary values and the game is played by projecting rings onto the board by means of a mechanical device designed for this purpose and operated by a light 60 blow of the finger. This projecting device or catapult is shown in Figs. 2 and 3. It consists of a base block 6 generally wedge shaped in form and carrying a projecting board 7 upon which the rings are placed 65 before being snapped. The board is so placed that when the ring is placed on one end a slight blow of the finger on the opposite end snaps the ring in the air, causing it, when the catapult is properly located 70 and the blow properly given, to fall on the board with a chance of falling over one of the pins.

In order to get the proper tilting connection between the base and the projecting 75 board, I form on the inclined face of the wedge shaped block a ridge or projecting angle 6^a extending transversely across the block from side to side. This construction gives two plain surfaces 6^b and 6^c making 80 an angle with each other and separated by the angle 6^a. The board 7 is so pivoted to the block as to rock on the angle 6^a and tilt from one surface to the other. The board 7 is formed with a transverse groove 9 on its 85 upper side and within this groove lies a staple 8 which enters the top of the block at each side of the board forming thus a pivoting connection which allows the board to tilt to a limited extent. The board 7 in 90 order to retain the ring 11 has formed on its lower end a flange or projection 10 and on its upper end a shoulder 12. When the ring is placed on the lower end its weight brings the board down onto the surface 6^b 95 leaving the upper end raised slightly above the surface 6^c. If, now the upper end of the board be struck sharply with the finger the ring will be tossed in the air. If, on the other hand the ring is placed on the upper 100 end of the board, that end is brought down to rest on the surface 6^c leaving the lower end raised slightly above the surface 6^b. If the lower end of the board is now struck the ring will be tossed in the air.

In playing the game as I prefer to play it one of the rings 11 is placed either on the lower or upper end of the projecting board 7, the base block is held down to the surface of the table by one hand and the free end 110

of the board 7 is struck lightly by one of the fingers of the other hand.

The block is held in any desired position away from the board 1. Each player in 5 turn plays a definite number of pins and the score is counted by adding the numbers on the pins caught by the rings played.

The game may be played in variety of ways and various modifications may be made 10 in the construction of the apparatus without departing from my invention as defined in the claims.

The apparatus may be very cheaply built by using pulp board for the box and it may 15 thus be sold at a low price.

The catapult may be used for projecting other articles beside rings and for playing other games which depend on projecting playing pieces onto a board.

20 In Fig. 5 I have shown a catapult embodying my construction but adapted to toss a ball or marble into the air.

Referring to the drawing, the board 13 is pivoted to the block 15 in the same way as 25 already described and a recess is formed in the lower end of the board which will retain a ball or marble 14.

I claim:

1. A catapult for projecting rings consisting of a wedge-shaped base block, the 30 inclined face of which has a transverse ridge or angle, a ring projecting member pivoted on said ridge or angle and adapted to tilt thereon.

2. A catapult for projecting rings consisting of a wedge-shaped base block, the 35 inclined face of which has a transverse ridge or angle, a ring projecting member having a transverse groove in its upper surface and a staple fitting in said groove and extending 40 into said block at each side of the member for pivoting the same on the ridge or angle.

3. A catapult for projecting rings consisting of a wedge-shaped base block, the 45 inclined face of which has a transverse ridge or angle, a ring projecting member pivoted on said ridge or angle and having at its lower end a projecting flange for holding a ring in place.

In testimony whereof I have affixed my 50 signature.

JEROME WARREN CHASE.
